UNITED STATES PATENT OFFICE.

NILS H. ANDERSON, OF BRIDGEPORT, CONNECTICUT.

TAPPING-MACHINE.

1,302,271.

Specification of Letters Patent. Patented Apr. 29, 1919.

Application filed January 27, 1917. Serial No. 144,820.

To all whom it may concern:

Be it known that I, NILS H. ANDERSON, a citizen of the United States, and resident of Bridgeport, in the county of Fairfield and 5 State of Connecticut, have invented certain new and useful Improvements in Tapping-Machines, of which the following is a specification.

This invention refers to improvements in 10 variable speed tapping machines such as are employed for tapping small holes in relatively light pieces.

The object of the invention is to provide a form of machine for the above purpose having 15 means for securing various speeds for different sizes of taps; also to produce a machine with what is known as an individual electric motor drive, and which will be in every respect a first class machine tool.

20 Another feature of the invention is to include lubricating means for the tap, so that as it passes through the work being operated upon it will run into oil. A further feature of the machine is to include a variable speed 25 in which the length of time necessary to complete an operation, that is, the tapping of the piece and the returning of the tap, will be the same, no matter what speed the spindle may be run in a forward direction, that

30 is, when the tap is entering the work. Another object of the invention is to produce what is known as a friction driven tapping machine in which the relative surface speed throughout the width of the effective frictional contact of the driven members is the same as that portion of the surface of the driver engaged by said driven members.

The foregoing and other objects of the 40 invention are attained by the mechanism illustrated in the accompanying four sheets of drawings forming a part of this specification, and in the various views of these drawings, like parts are designated by corresponding characters of reference, and in 45 which—

Figure 1 shows a perspective view of the machine as it would appear ready for use.

Fig. 2 shows a side elevation of my improved form of machine complete.

50 Fig. 3 is a central vertical section through the table of the machine taken on line 3 of Fig. 4.

Fig. 4 shows a front view of the machine as seen in Fig. 2.

55 Fig. 5 is a plan view, the same being illus-

trated on a somewhat larger scale than the previously described illustrations.

Referring in detail to the characters of reference marked upon the drawings 5 represents the main frame which includes a bed 60 portion 6, and arms 7—7 in which the spindle 8 is rotatably mounted. The machine is adapted to be secured to a table or bench 9 of any suitable or preferred construction by means of screws 10. The spindle 8 referred 65 to is mounted to rotate in ball bearings 11 housed in the arms 7 of the frame and inclosed by caps 12 fitted upon the top of the arms and around the spindle. Upon that portion of this spindle arranged between 70 the arms 7—7 are secured, upper and lower friction members 13 and 14 having peripheral working surfaces of the same relative diameter throughout the width of their faces as that of the spherical disks. Upon the 75 lower end of the spindle is secured a chuck 15 in which the tap 16 is detachably held. Upon the upper end portion of the spindle and between the arm 7 and nuts 17, see Fig. 2, is mounted a spring 18 which is for the 80 purpose of balancing the weight of the spindle and parts carried thereon so as to make the movement of the spindle upward easily accomplished. This spring is made adjustable to regulate its tension upon the spindle 85 by the adjustment of the nuts 17, one of which obviously serves as a lock nut to insure the holding of the lower nut in position when set. The upper end of the spindle, including spring and nuts, are inclosed by a 90 removable cap 19. The sleeves 20 fitted in the upper and lower arms 7, together with the ball bearings, serve to operably support the spindle 9 which is susceptible of a slight endwise movement, as will later be 95 again referred to.

An electric motor 12 is pivotally mounted at 22 in the two parallel walls of the frame and is adapted to be swung upon its pivots to bring its motor shaft into various angular 100 positions where it is secured by means of the clamping screw 23 that freely passes through the circular slot 24 in the side wall of the frame of the machine and engages the motor. A spherical faced disk 25 is secured to 105 the motor shaft and serves as the means for transmitting motion from the motor and with which the friction members 13 and 14, of the tapping spindle engage.

From the foregoing it will be evident that 110

if the spindle is lifted it will cause the lower friction member 14 to come in contact with the central spherical face portion of the driving friction cone 25 and just below the central line of the motor shaft and cause the friction member and spindle to be rotated forward in the direction indicated by the arrow *a*. On the other hand, if the spindle is drawn down, the friction member 13 will come in contact with the outer face of the driving disk above its center, causing the friction member 13 and the spindle to be rotated in a backward direction as indicated by the arrow *b*. Therefore if it should be desired to change the relative speeds of the friction members 13 and 14 the same could be accomplished by releasing and swinging the motor so as to bring its shaft to a different position, thereby raising or lowering the driving member.

A bracket 26 having a forwardly extended arm 27 is adjustably secured to the base of the frame. A pair of vertically disposed guide rods 28 are secured in this arm, and serve to support the work table 29. This work table comprises a top plate that is mounted upon a cylindrical carrier 30 having arms 31 with aligned holes to accommodate the guide rods 28 upon which said arms slide, to raise and lower the table. This cylindrical carrier is hollow, forming an oil reservoir, the lower end being closed by means of a plug 32 which is threadably attached thereto. In practice this cylinder is filled with oil so that when the tap passes through the work and the hole in the table it will dip into the oil, thus lubricating the end of the tap for the next piece of work to be operated upon. This dip also serves to remove the chips from the end of the tap which might otherwise cause injury while the tap is being returned to its normal position.

Movable stop collars 33 and 34 are provided upon the guide rods 28 to permit the table to be adjusted slightly, should occasion require. The upper end of an adjustable spring 35 is secured to a screw 35^a in the arm 27 and extends down through a hole in the upper arm 31 and is engaged at the lower end by a screw 36 secured to the lower arm 31 in a manner to yieldably support and balance the weight of the table.

As above stated the work table is adapted to be raised and lowered to carry and feed the work to and from the tap. This table is preferably operated by a flexible foot lever connection as shown in Figs. 1, 2 and 3, and comprising an arm 37 that is secured to one of the guide rods 28, and serve to support the lever 38 pivoted thereto. The forward end of this lever engages a shoe upon the under side of the arm 31 of the work table in a way to raise the same when the inner end of the lever 38 is drawn down.

A vertically disposed rod 39 is pivotedly connected to the inner end of the lever 38. This rod is adjustably connected to a second vertical rod 40, the lower end of which is pivotedly connected to an arm 41 secured to the pedal rocker shaft 42 mounted in brackets 43 and carrying a pedal 44.

Loosely mounted on rod 40 is a compression spring 51 which is held between two collars 46 and 49. This spring serves to give a yielding connection between rods 39 and 40 when such yielding connection is desirable for the proper operation of the machine. By tightening screw 45 in block 36 and leaving screw 47 loose, also tightening screw 48 in block or collar 49, leaving screw 50 loose, the motion from the treadle mechanism will be transmitted through lever 41, rod 40 through the spring 51 to rod 39. Collar 52 serves to prevent excessive or lost motion in the return of the treadle mechanism and the rods to the normal position. This collar is mounted on rod 40 adjacent to collar 49.

In the practical operation of my improved tapping machine the operator places and holds the work to be tapped upon the table and then operates the pedal in a way to raise the table and work to the tap. The engagement of the work with the tap causes an upward pressure upon the spindle which brings the lower friction into engagement with the lower side of the spherical driving members. This will cause the spindle and tap to run to the right and through the piece of work. When the operation is completed the pedal pressure is released causing the table and spindle to drop slightly and the lower friction to disengage and the upper one to engage, thus reversing the direction of the rotation of the spindle and thereby running the tap backward out of the work.

From the above it will be seen that the foregoing construction of machine comprises a practical form of tapping machine having a great many advantages—the main feature being that the time for operation is the same no matter at what speed the tap spindle is rotated in either direction, that is, if the ratio between the driving disk 23 and friction members 13 and 14 is such as to be equal in both directions and that speed is 2000 R. P. M. forward and 2000 R. P. M. reverse. The motor may be changed so as to secure 1000 R. P. M. in the forward direction, the speed will then be increased in the reverse direction to 3000 R. P. M. so that the combined figure of 4000 is maintained.

Having thus described my invention what I claim and desire to secure by Letters Patent is:

1. In a tapping machine of the class described, the combination of a frame, an electric motor pivotedly mounted in the frame, a spherical driving disk mounted upon the

motor shaft and adapted to be raised and lowered by the pivotal adjustment of the motor, means for securing the motor in its adjusted positions, a longitudinally movable 5 tap spindle, a pair of friction members secured thereto and adapted to engage the opposite sides of the spherical disk, a vertically movable work table, means for raising and lowering the table, and means for yieldably 10 supporting the weight of the table.

2. In a tapping machine of the class described, the combination of a frame, an electric motor pivotally mounted in the frame, a spherical driving disk mounted 15 upon the motor shaft and adapted to be raised and lowered by the pivotal adjustment of the motor, means for securing the motor in its adjusted positions, a longitudinally movable tap spindle, a pair of friction members secured thereto and adapted to engage the face of the spherical disk, a spring to balance the spindle, a vertically movable work table, a spring to yieldably 20 support the weight of the table and means 25 for raising and lowering the table.

3. In a tapping machine of the class described, the combination of a frame, an electric motor pivotally mounted in the frame, a spherical driving disk mounted 30 upon the motor shaft and adapted to be raised and lowered by the pivotal adjustment of the motor, means for securing the motor in its adjusted positions, a longitudinally movable tap spindle, a pair of friction members secured thereto and adapted to engage the face of the spherical disk, a vertically movable work table having a hole 35 therein, an oil reservoir beneath and carried by the table, means for raising and lowering the table, and means for yieldably 40 supporting the table.

4. In a tapping machine of the class described, the combination of a frame, an electric motor pivotally mounted in the frame, a spherical driving disk mounted 45 upon the motor shaft and adapted to be raised and lowered by the pivotal adjustment of the motor, means for securing the motor in its adjusted positions, a longitudinally movable tap spindle, a pair of friction members secured thereto and adapted to engage the face of the spherical disk, on the opposite sides of the axis, a vertically 50 movable work table, a bracket for supporting the table, means for raising and lowering the table, and a spring for yieldably 55 supporting the table.

5. A tapping machine of the class described, comprising a main frame, a longitudinally 60 movable tap spindle, a tap carried by said spindle, an electric motor pivotally mounted in the frame and connected to drive the spindle, a vertically movable work table, means for raising and lowering 65 the table, means for moving the tap spindle

endwise by the pressure of the work on the tap for the purpose of reversing the drive of the tap spindle.

6. In a tapping machine of the class described, the combination with a main frame, 70 a tap spindle mounted in the frame, a pair of friction members secured to the spindle, an electric motor pivotally mounted in the frame and having a spherical driving disk upon its shaft, said motor being capable 75 of adjustment in the frame to vary the speed of the tap spindle.

7. In a tapping machine of the class described, the combination with a main frame, 80 an electric motor pivotally mounted therein and adapted to be adjusted and secured in various positions, a tap spindle, a pair of friction members mounted thereon and having peripheral surfaces to conform to that of the surface of the spherical disk when 85 adjusted to any position and to obtain the maximum drive and efficiency of the machine at all times.

8. The combination in a tapping machine of the class described of a main frame, a 90 vertically disposed and endwise movable spindle mounted therein, a pair of friction members, a chuck suitable for holding a tap mounted on the lower end of said spindle, an electric motor pivotally mounted in 95 the frame and having a substantially horizontal shaft, a spherically faced disk mounted on said motor spindle adapted to engage the two friction members alternately for the purpose of rotating the tap 100 spindle first in one direction and then in the opposite, a vertically movable work table mounted on suitable slide rods under and adjacent to the tap, means for operating said table by foot treadle mechanism 105 comprising a pair of connection rods, a spring loosely mounted on one of the pair of rods, suitable stop collars for adjusting the spring all and for the purpose described. 110

9. In a tapping machine of the class described, the combination of a main frame, an electric motor pivotally mounted therein, a spherically faced disk mounted on the motor shaft, a vertically disposed tap spindle mounted in the frame, a pair of friction members mounted on the spindle, a spring loosely mounted on the said vertically disposed spindle, and means for adjusting the tension of said spring to balance the weight of the spindle and associated parts. 115

10. In a tapping machine of the class described, the combination with a main frame, of an electric motor pivotally mounted 120 therein, a spherically faced disk mounted on the motor shaft, a tap spindle, a pair of friction members mounted thereon so adjusted as to permit endwise movement of the spindle for the purpose of alternately 125 130

engaging and disengaging the frictional members with the spherically faced disk without disturbing the location of said disk.

11. In a tapping machine of the class described, the combination with a main frame, of an electric motor pivotedly mounted therein, a substantially horizontal shaft mounted in the motor, a spherically faced disk mounted on the shaft, a tap spindle having a pair of friction members mounted thereon so adjusted as to permit endwise movement of the tap spindle for the pur-

pose of alternately engaging and disengaging said friction members and face of spherical disk without effecting the location of motor spindle. 15

Signed at Bridgeport, in the county of Fairfield and State of Connecticut, this 25th day of January, A. D., 1917.
